CARBURIZING BOX

Henry H. Harris, Boston, Mass.

Application September 14, 1934, Serial No. 743,984

6 Claims. (Cl. 263—49)

This invention relates to carburizing boxes and is an improvement on the invention of my Patent No. 1,882,580.

It is an object of my invention to provide a carburizing box which will stand up better and longer under the severe usage which such boxes receive.

It is a further object of my invention to provide a carburizing box which will have a longer service life in proportion to the difficulty and expense of making same.

Other objects will appear in the course of this specification.

When carburizing boxes are to be used in heat treating furnaces, metal articles to be carburized are placed in the boxes, together with a carburizing agent such as bone dust. Trays are placed over the boxes, the boxes with their trays are then usually inverted, and in this position are subjected in a heat treating furnace to heat usually supplied from beneath.

The boxes must stand up under rough handling, extremely high temperatures, sudden changes in temperature, and the pressure of a heavy load of contents while softened by heat, all with attendant warping and buckling, producing cracks and ultimately finally breaking the box down.

As a result, if the boxes were not made so as to have great durability under such treatment they would have to be replaced constantly at great expense, and it becomes a problem of some nicety and importance to devise a box having the longest life in proportion to the cost of producing same, in which my invention which is illustrated in the drawing herewith represents an advance over the art.

In said drawing,

Fig. 1 is a plan view of a box constructed in accordance with my invention;

Fig. 2 is a section thereof taken on line 2—2 of Fig. 1; and

Fig. 3 is a detail section on line 3—3 of Fig. 1.

The box is made up of five parts, one cross part 10, and four corner parts 12a, 12b, 12c, and 12d.

The cross part 10 is made of a material more flexible under operating conditions and more capable of absorbing strains without cracking or giving way. This material is preferably a sheet of high grade ductile heat resistant alloy, such as high nickel chromium alloy which is low in iron content.

The corner parts 12a, 12b, 12c, and 12d are preferably made of relatively inexpensive cast

metal, preferably nickel-chromium-iron alloy with high iron content.

The cross part is formed with one or more corrugations running lengthwise of each of the four arms thereof. In the embodiment shown in the drawing as illustrative of my invention, there are three corrugations in each arm. The front, inward corrugation of end arm 10a continues around and becomes the left, inward corrugation of front arm 10d; the right, inward corrugation 10 of front arm 10d continues around and becomes the front, inward corrugation of right arm 10c; the back, inward corrugation of arm 10c continues around and becomes the right, inward corrugation of back arm 10b; the left, inward corrugation of arm 10b continues around and becomes the back, inward corrugation of left arm 10a.

The center corrugations of all the arms are outward and lead to the center of the floor of the box where they broaden and merge. Preferably at the center where the axes meet I provide a circular raised mound 20, the purpose of which will appear hereinafter.

It will be obvious that the edge corrugations could be downward and the center ones upward, and that various numbers of corrugations other than three could be provided. In fact, a single corrugation to each arm could be used instead of the three shown. Furthermore, the central area where the center corrugations merge could be given a shape other than the one shown. The form shown is, however, preferred because while relatively simple it gives great flexing and absorbing of strains.

The four corner parts are each three sided, each forming part of the floor, an end wall, and a side wall of the carburizing box. These corner parts are secured to the cross part preferably by being cast around the edges of the cross part with fork flanges 14, 16 embracing same. Holes 18 are formed in the cross part along the edges thereof, and when the corner parts are cast thereabout their fork portions are joined through the holes, securely anchoring the parts together.

Because the corner parts are open, with their sides extending at right angles to each other, casting thereof is facilitated, they can be cast thinner, and there will be fewer casting strains as in casting the metal does not have to flow so far and around such devious courses as would be the case in casting, for instance, an entire integral box.

In operation the relatively flexible, heat resistant, strain absorbing material of the cross

part is free to flex all the way across along either major axis or both, allowing the box to swell and shrink and bend without straining and breaking down the more brittle cast corner parts, such strains being taken up and such flexing occurring along the central corrugations which extend all the way across the cross piece in both directions.

Moreover, local warping, which may vary at different points, will be absorbed by the two outer corrugations along each arm and will therefore not tauten and twist the center corrugation but will leave it free to bend easily in accomplishing its purpose of accommodating the strains of greater extent.

15 When the entire box bends along one axis, say upward along the longitudinal axis, and then bends upward along the transverse axis, a concentrated strain is created at the very center. While a flat surface at this point will work, the 20 box will stand up longer if means is provided to take care of the strain at this crossing point. This the mound 28 does by providing what may be called a reservoir of material, which can stretch out where there is a pull or close in where 25 the material is squeezed. Hence these local strains will be absorbed over a larger area instead of being concentrated at one point.

I claim:

1. A metallic receptacle for use in heat treating furnaces comprising a cross part having four arms extending out along the bottom from their common center and then up the sides, four corner parts secured to the cross part to form a rectangular box, and a corrugation extending the 35 full length of each pair of opposite arms, said corrugations merging at the crossing point.

2. Device of claim 1 in which the cross part is formed of a more flexible metallic material than the corner parts.

3. Device of claim 1 in which the cross part is formed from a sheet of high grade relatively flexible heat resistant alloy and the corner parts are formed of relatively inexpensive cast metal.

4. Device of claim 1 in which the common area in which the cross corrugations merge is generally planar and is distended into a circular mound 10 at the center.

5. Device of claim 1 in which the therein mentioned corrugation is centrally disposed and an oppositely curved corrugation flanks it on each side, said flanking corrugations curving off near 15 the center of the receptacle and following along the edges of the corner parts.

6. A metallic receptacle for use in heat treating furnaces comprising a four arm cross part of high grade relatively flexible heat resistant 20 alloy, the crossing and the inner parts of said arms being generally horizontal and the outer parts of the arms extending upward, corner parts formed of relatively inexpensive cast metal secured to said arms and being so shaped as with 25 the cross to form a box, a plurality of lengthwise corrugations formed in each arm, a central one of said corrugations in each arm continuing and merging with the corresponding corrugation of the opposite arm, and the edge corrugation of 30 each arm curving around the corner of the adjacent corner part and merging with the corresponding corrugation of the adjacent arm.

HENRY H. HARRIS. 35
